UNITED STATES PATENT OFFICE.

ROBERT W. THOMSON, OF LYNN, MASSACHUSETTS, ASSIGNOR, BY MESNE ASSIGNMENTS, TO PHILADELPHIA BARRING MACHINE COMPANY, OF CAMDEN, NEW JERSEY, A CORPORATION OF NEW JERSEY.

THREAD-CUTTER FOR SEWING-MACHINES.

SPECIFICATION forming part of Letters Patent No. 691,676, dated January 21, 1902.

Application filed October 15, 1900. Renewed September 25, 1901. Serial No. 76,531. (No model.)

To all whom it may concern:

Be it known that I, ROBERT W. THOMSON, a citizen of the United States, residing at Lynn, in the county of Essex and State of Massachusetts, have invented a new and useful Improvement in Thread-Cutting Mechanism for Sewing-Machines, of which the following is a specification.

My invention is an improvement upon sewing-machines of the class wherein a thread-cutting mechanism operates automatically and simultaneously with the stopping of the machine to cut the threads, and thus prepare the machine for a succeeding operation. An example of machines of this class is found in the sewing-machine described in Letters Patent of the United States No. 545,391, issued to me August 27, 1895, and further development of such machines is illustrated in Letters Patent of the United States No. 660,130, issued to me October 23, 1900. The successful and accurate operation of such machines requires the cutting-blades to be located very close to the under side of the throat-plate of the machine and to pass close to the needle-hole, in some instances to pass directly under the needle-hole in the path of the needle. When the cutting mechanism is in proper condition, the retracting-spring connected therewith may be relied on to retract the cutter-blade from the immediate vicinity of the needle-hole; but when this mechanism is slightly gummed, or if a piece of thread gets caught in the blade and retards the retractile movement, there is serious liability to damage, because the needle descends almost instantaneously upon restarting the machine.

My invention presently to be described provides positive means for moving the thread-cutting cutter out of harm's way when the machine is started.

In the drawings, Figure 1 is a side view of a machine of the character described with my improvement attached. Fig. 2 is a view in perspective of the cutter-retracting mechanism with the machine-frame indicated by dotted lines. Fig. 3 is a detail of a portion of the mechanism shown in Fig. 2, and Figs. 4 and 5 are illustrations of parts of the automatic stop mechanism.

The stopping and starting mechanism and the connected parts which actuate the cutter

when the machine is stopped are for the sake of brevity in description here shown as substantially the same as those of the machine described in my aforesaid Patent No. 660,130 and are lettered in the drawings as in the drawings of the said patent. The machine-bed 1, arm 2, needle-shaft N, throat-plate P, cutter and cutter connections C, shipper mechanism S, starting-lever and connections A and cutter-actuating systems L and M are substantially as shown in the said Patent No. 660,130 and operate in substantially the same way upon the stopping of the machine. 65

I have shown herein a machine which operates through a definite stitch cycle determined by the cam O, journaled at O², which is driven by the worm O³ on the needle-shaft N and which controls the movements of the cloth-holding clamp. The stitch cycle is completed by a single revolution of the cam O, and upon the completion of each revolution of the cam the machine is automatically stopped. Reference to my Patent No. 545,391 75 will sufficiently explain the relationships of working parts by which a cam, such as O, controls the stitch-forming mechanism.

When by the depression of the starting-lever a⁴ a⁵ the shipper-fork s' moves the belt 80 from loose pulley p² to fast pulley p', the shipper-block s³, pivoted at s⁵, is moved against the shipper-spring (not herein shown) to a position where the spring-actuated shipper-detent H (see Figs. 4 and 5 for details) catches 85 and holds the shipper-block s³ by its hook h³. So long as this condition is maintained the machine must run. As the rotation of the cam O nears its completion the tripper-dog t, secured to the back side of the cam O, Figs. 90 4 and 5, crowds in the end h' of the shipper-detent and releases the shipper-block s³ from the hook h³, Fig. 4. The shipper-spring thereupon throws the belt back to the loose pulley, and only the momentum of the working parts 95 of the machine remains to cause continuance of movement. At the moment when the shipper-detent is released the block o', secured to the face of the cam O and properly beveled, passes under the toe r of the initial-movement lever system L and causes the blade c' of the cutter to enter and engage the thread-loop. At this point the machine stops, in the manner and by the means shown in my Pat-

ent No. 660,130, and the lever system M gives the cutter its final movement. Then the machine rests, with the block o' and toe r in contact and the cutter-blade consequently advanced and in or near the path of the needle.

In order to insure positive retraction of the cutter before the initial descent of the needle in the next sewing operation, I provide a cutter-retractor system, which is embodied in the mechanism now to be described.

The train of mechanism consists of a rod or plunger W, loosely supported in holes w^2 w^3 , made in the machine neck and bed, respectively. The upper end w' of the rod W is rounded and adapted to make operative contact with the cam U, which is secured to the needle-shaft N. The lower end of rod W is operatively connected with the cutter-lever by means of a bell-crank lever w^5 w^6 , pivoted at w^6 and jointed to the rod W at w^4 . The arm w^7 of the bell-crank lever makes contact with the cutter-lever, or, if necessitated by the location of the cutter-lever, with an extension-arm, as c^{11} , which is preferably adjustable on the cutter-lever, as at c^{12} .

When the machine is in operation and before the cutter-actuating mechanism is in play, the stress of the spring c^9 throws the end c^{10} of the cutter-lever outward, and thus permits the rod W to fall slightly. The proportions of the parts described are such that when the rod W is in its lowest position during the operation of the machine the cam U rotates idly, its high side u^2 just missing the end w' of the rod W. When, however, the machine stops, the action of the block o' on the cam O through the connections heretofore described throws the cutter-lever end c^{10} inward and lifts the rod W at the same time that it gives the cutter-blade its initial movement. The cam U is so proportioned that its low side u' is over the rod W when the latter is lifted by the action of the block o'; but at this point the machine stops and the parts are left as shown in Figs. 1 and 2. When the machine is again started, the first rotation or partial rotation of the needle-shaft N in the direction indicated by the arrow, Fig. 2, brings the high side u^2 of the cam U down on the end w' of the rod W and positively throws the cutter-lever over, retracting the cutter-blade from the position of danger. The proportions of the cam U and the connecting mechanism are such that positive retraction of the cutter is inevitable before the needle descends through the throat-plate.

It is to be observed that the positive depression of the rod W and movement of the cutter-lever take place before the toe r of the lever system L is freed from contact with the block o'. If all the parts of the lever system L were rigid, the forcible depression of the rod W would involve breakage somewhere. This is provided for by the insertion of an elastic member in the lever system L. The specific structure by which this is accomplished is shown in detail in Fig. 3. A stud

n is secured to the lever end l' and bored out at n' and n^2 to receive the toe r, stem r' , and spring r^4 . A collar r^2 and binder-screw r^3 serve to secure the stem r' at any desired point of adjustment.

The spring r^4 is a stiff one, sufficiently so to render the toe r substantially rigid while the cutter-actuating movements are being made. In response to the forcible action of the cam U and rod W the spring r^4 is compelled to yield and permits the positive retractile movement of the cutter to take place without injury to any part of the machine. The first complete revolution of the shaft N carries the cam O forward and withdraws the block o' from the toe r, so that the cam U on its next revolution rotates idly, the rod W having dropped out of range by reason of the relaxed condition of the connected parts.

If the character of the machine permits the employment of a block o' or analogous device and a toe r or its equivalent, so nicely proportioned and adjusted that the initial movement of the machine removes these parts from contact relationship before the retractor mechanism comes into operation, the elastic member may be omitted; but in most instances some such yielding part as that described will be found desirable. It is to be observed, also, that if the spring c^9 should be broken or should not be attached to its anchorage in the proper manner the cam U will at any time during the operation of the machine guard against accidental displacement of the cutter. The high side of the cam U travels over the rod W before and to some extent during the descent of the needle.

The above-described positive cutter-retracting mechanism is adapted for use on machines of the character described in my aforesaid Patent No. 660,130, as well as on machines wherein a pattern-cam, such as the cam O, is employed to determine the character and duration of the stitch cycle.

The peculiar structure and operation of the machine shown in my said patent render the presence of an elastic member in the lever system L unnecessary.

From the foregoing description it will be observed that the present improvement relates more particularly to the thread-cutters in which a cutting or severing member is arranged and adapted in performing its normal function to cross the line of reciprocation of the needle while the latter is raised and that its essential feature consists in the combination, with means for actuating such cutting or severing member, of means independent thereof for positively insuring the retraction of the said member before the succeeding descent of the needle, and that the specific character of the said retracting means and the actuating device therefor are not, therefore, material parts of the improvement.

What I claim, and desire to secure by Letters Patent, is—

1. In a sewing-machine of the character in-

dicated, wherein a stop-motion and thread-cutting mechanism are associated, the combination of a thread-cutting knife, situated in close proximity to the needle-path through the throat-plate and movable across said needle-path, a cutter-retractor operatively connected with the cutter and so timed with relation to the vibrations of the needle-bar that the cutting-knife is positively automatically retracted upon starting the machine, and withdrawn from the needle-path before the needle descends through the throat-plate.

2. In a sewing-machine of the character indicated, wherein a stop-motion and thread-cutting mechanism are associated, the combination with a thread-cutter situated in close proximity to the needle-path through the throat-plate and movable across said needle-path, of a cutter-actuator consisting of a positively-driven train of mechanism of which one part is an elastic member, connections between the actuator and the cutter, a cutter-retractor, connections therewith to the cutter, mechanism connected with the driving-shaft of the machine whereby, upon starting the machine, the cutter and its connections are positively moved by the retractor in a direction opposite to that effected by the actuator, the elastic member of the actuator serving to cushion the said retractile movement.

3. In a sewing-machine of the character indicated, wherein a stop-motion and thread-cutting mechanism are associated, the combination of a cam secured to the needle-shaft, cutter-retracting mechanism connected at one end with the cutter mechanism and at the other end in operative conjunction with the cam, so that the cam operates on the retracting mechanism when the cutter and its connections are in cutting position.

4. In a sewing-machine of the character indicated, wherein a stop-motion and thread-cutting mechanism are associated, the combination of cutter-actuating devices and cutter-retracting mechanism connected with the cutter, a cam secured to the machine-shaft, the cam and cutter-retracting mechanism being so proportioned and disposed that the cutter-retracting mechanism is advanced into operative conjunction with the cam when the cutter-actuating devices act to operate the cutter, and is withdrawn from said operative conjunction when the cutter-actuating devices are idle and the cutter retracted.

5. In a sewing-machine of the character indicated, wherein a stop-motion and thread-cutting mechanism are associated, the combination of a cutter-actuator provided with an elastic contact member, connections between the actuator and the cutter, a cutter-lever, a cutter-retractor comprising a retractor-lever in contact with the cutter-lever and connected with an operating-rod, a cam on the machine-shaft, the cam and rod so proportioned and disposed as to make contact with each other when the machine is

started and the cutter is in the position determined by the operation of the actuator.

6. In a sewing-machine of the character indicated, the combination with a thread-cutting device, of means for actuating the same to cut the thread, and positively-actuated means independent thereof and acting automatically to insure the return of said thread-cutting device to initial or inoperative position before the beginning of the succeeding stitch.

7. In a sewing-machine of the character indicated, the combination with stitch-forming devices including a reciprocating needle, and a thread-cutting device with means for actuating it, of means independent of said actuating means whereby said thread-cutting device is positively prevented from remaining in cutting position when the needle descends below the work-plate.

8. In a sewing-machine of the character indicated, the combination with the stitch-forming mechanism, and a thread-cutter with means for positively actuating it, of a spring for retracting said cutter, and positively-actuated means for insuring the retraction of said cutter before a predetermined stage of the operation of the stitch-forming mechanism.

9. In a sewing-machine of the character indicated, the combination with stitch-forming mechanism including a reciprocating needle, a thread-cutting knife or cutter movable transversely of the line of reciprocation of said needle, and means for positively actuating said cutter while the needle is elevated above the work-plate, of means for positively insuring the retraction of the cutter before the succeeding descent of the needle.

10. In a sewing-machine of the character indicated, the combination with stitch-forming mechanism including a reciprocating needle-bar and needle and means for actuating the same, of a thread-cutter and means for actuating it to sever the thread while the needle is elevated above the work-plate, and means connected directly with the needle-bar-actuating devices but independently of the needle-bar for positively insuring the retraction of the thread-cutter while the needle is still elevated above the work-plate.

11. In a sewing-machine of the character indicated, wherein a stop-motion and thread-cutting mechanism are associated, the combination with the thread-cutter arranged and adapted to operate across the line of reciprocation of the needle, of a cutter-retractor operatively connected with the cutting mechanism, and means whereby the retractor is positively automatically actuated upon starting the machine.

Signed by me at Boston, Massachusetts, this 12th day of October, 1900.

ROBERT W. THOMSON.
